Richard E. Freeman, Beloit, Wis., assignor to
Freeman Shoe Corporation, Beloit, Wis., a cor-
poration of Wisconsin

Application October 27, 1943, Serial No. 507,855

2 Claims. (Cl. 36—8.5)

This invention relates to shoes and is particularly directed to an improved shoe design and structure that will enable a wearer with substantially normal feet to avoid many foot ailments induced by the faulty design and structure of conventional shoes.

Scientific study of the natural walking gait shows that the weight of the foot is first taken on the heel, then in rapidly rolling rotation from the small toe to the large toe along the outside of the foot onto the ball of the foot when the large toe shoves the body forward in a lever-like action as the heel is again raised in the walking gait. Dr. Arthur Steindler, professor of orthopedic surgery, University of Iowa, states the foot action as follows: "In walking, the foot is placed on the ground heel first: it then rolls over the outer border until the contact reaches the ball of the foot."

This usage of the foot is better understood upon considering the problem of balance in walking. It will be appreciated that one foot is taking the support of the body from the time the heel contacts the ground until the large toe leaves the ground, when the weight is shifted to the other foot. This swinging shift of body weight in walking motion is best accomplished by the "rolling over the outer border of the foot" as fully described and discussed by Dr. Steindler in his treatise "Mechanics of Normal and Pathological Locomotion in Man."

When the foot functions in this normal and natural manner, the tendons and muscles supporting the bone structure of the foot are utilized in effective coacting relationship to produce the almost effortless walking gait of the American Indian and other barefoot aborigines. Further it is worthy of note that such natural foot action induces a slightly toeing in stride so typical of the Indians.

Much attention and study has been given the intricate bone structure of the foot with its longitudinal and transverse arches. This intricate bone structure is dependent upon interconnected tendons and muscles to protect and keep these bones in proper functional relationship. Fallen arches are not due to bone failures per se: the failure of the tendons and muscles supporting the arches cause the arch to fail. One authority aptly states the case: "The integrity and form of the foot is entrusted first to the ligamentous and second to its muscular apparatus."

Moreover, the effectiveness of these ligaments and muscles in their coaction with the bone structure is largely dependent on the proper se-

quence of their use, because these tensioning ligaments are built up in an underlying coacting relationship with the bone structure that produces effective mechanical advantage in the foot arches. A study of the under surface of the foot showing continuations of tendons from leg muscles as shown in Toldt's Anatomical Atlas, clearly shows that the tendons from the toes overlie each other with the little toe tendon on the bottom and all intertwined under the inside of the foot. The tensioning of these tendons in the sequence induced by the gradual shifting of the weight from the little toe to the large toe produces a mechanical advantage to the foot arch that permits the arch to easily and naturally resist the stresses imposed. Further, when thus used, the foot functions in the natural slightly toed-in manner: contrariwise, when the weight is shifted along the inside of the foot, a toed-out 20 gait is induced which puts unnatural stress on the arch of the foot and may finally result in a series of foot ills ranging from bunions to broken arches.

In my improved shoe design I provide a structure which positively induces the foot to function in the natural manner by mechanically holding the heel firmly upright while slidably inclining the foot outwardly to carry the weight in the "roll over the outer border" manner until it rests 30 on the ball of the foot. The structure for accomplishing the above result largely resides in the heel and sole design of the shoe. However, in full appreciation of the important vital functions of the tendons and muscles of the foot I 35 form the upper to accommodate and mold the muscular tissues into the proper shape for this natural foot action.

This natural design of the upper structure is of major importance because it permits the muscular tissue to assume the proper position and shape to function naturally and properly. Although muscle tone for modern feet varies from the flabby feet of the sedentary office worker to the hard muscled feet of the professional ball 45 player, all muscular tissue should be positioned in the proper relationship to function in this one natural way. It will be appreciated that soft flabby foot muscles will not assume their proper form and functions—in fact they promptly tend 50 to assume misshapen shapes that are ill adapted to their natural function. It is my theory that regardless of muscle tone, the foot should be molded and held in proper form for natural coacting relationship of the muscles and bone structure. When this is done, the muscles tend to

function properly and the ill results of misplaced muscle tissue followed by mislocated bone structure are avoided.

The particular object of this invention is to provide an improved shoe design and structure to maintain the foot in proper alignment and induce the foot to function in a normal manner.

Further objects and benefits will be disclosed in the following description and drawings in which:

Fig. 1 is a perspective view of my improved shoe last with cross sectional outlines thereon and further showing the shapes and outlines of my formed inner sole and counter as will later be explained;

Figs. 2, 3, 4 and 5 are elevational views of the cross sections of my improved last at sections 2—2, 3—3, 4—4, and 5—5 respectively;

Fig. 6 is a broken perspective view of my improved shoe as provided by forming over the last shown in Fig. 1, to show the relationship of my formed inner sole and counter as will further be explained; and

Figs. 7, 8, 9 and 10 are elevational cross sections of the shoe as they would appear on the section lines 7—7, 8—8, 9—9 and 10—10 respectively.

I desire to explain and teach that the fundamental concept of my improved shoe design is to provide a solid cupped socket for the heel to fit its natural shape as it supports its normal weight. I form these heel sockets in my improved shoe to provide a strong solid heel support that will hold the heel in firm upright natural relationship. I reject any suggestion of a resilient or cushioning structure of the heel because such structure is opposed to my theory of an anchored heel socket firmly attached in proper relationship to the balance of the shoe. I maintain that the natural cushion of the human heel pad is fully sufficient in itself as a cushion if permitted to assume its natural position and shape for normal weight and shock.

With the heel thus firmly and naturally supported, I fasten the balance of the shoe in firm natural relationship to the heel. It is my concept that this natural relationship will provide for a "rolling over the outer border of the foot" action and when the foot is permitted to function in this manner, most of the foot ailments are avoided. I therefore provide shoe structure which definitely induces the weight to be borne in this natural manner and further provide structure to support the stresses thus induced in order to maintain the shoe in proper shape. Again, I reject any idea of cushioning; the structure I provide being firm and strong to operate as effective mechanical means to attain this result.

Now referring to Figs. 1 to 5 inclusive, and at the outset particularly to Fig. 1; I designate the center line of the last by the line 11—11 which is actually the center line of support, but not the geometric center line of the shoe. It is the line drawn from the center of the rear of the heel of the last to the center of the toe of the last. I designate the vertical plane from the center line 11—11 by the center lines 12—12. The various cross sections shown in Figs. 2, 3, 4 and 5 show the shape of the last as it would appear on the section lines 2—2, 3—3, 4—4 and 5—5, respectively. I show in outline on the last the position of my formed insole 17 and my counter 18 in relation to the various cross sections 2 to 5, inclusive.

Now referring to Figs. 6 to 10 inclusive, I show in Fig. 6 my improved shoe as it would be formed on the last shown in Fig. 1, broken away to show

my formed inner sole 17 and counter 18 in relation to the balance of the shoe. In Fig. 7, I show a cross section as it would appear on the section line 7—7 corresponding to the section 2—2 on the last of Fig. 1. It will be observed that the shape of the shoe at the center of the heel is generally pear-shaped and closely follows the shape of the heel of a normal foot when supporting its weight. It will be observed that the major portion of the heel section is on the outside of the center line 12—12 and that the heel 15 is hollowed out in order to accommodate my formed counter 18 and inner sole 17 in the natural pear-shape of the normal human heel as it supports its weight in wet sand. I desire to point out and teach that this structure provides strong mechanical means to hold the heel in its natural weight-bearing shape and is a decided improvement over conventional square cornered heel structures which are ill-adapted to resist the stresses imposed. The formed inner sole 17 supports the weight directly on the heel 15 and protects the formed counter 18 from sidewise leverage movements by reinforcing the counter well above its contact with the heel 15. This is a far better mechanical structure for resisting sidewise stresses than a flat bottomed heel because counter 18 is well supported above its bottom contact with the heel 15 and thus presents a much shorter leverage for sidewise stresses. It will be well understood that I form my inner sole 17 from heavy leather formed and stiffened to provide a smooth curved side wall support for the bottom of the foot.

Now referring to Fig. 8 it will be observed that the greater area of the cross section is again carried to the outside of the center line 12—12 of the shoe and that the inner side of the formed inner sole 17 is supported by strong leather section 16 affixed to the sole 14. This structure mechanically throws the weight to the outside of the shoe because the smooth formed inner sole 17 being tilted toward the outside would naturally slide the weight to the outside where it is supported by my strong inner sole structure. It will be observed that the upper 19 in relation to the inner sole 17 and its support 16 is protected against the stresses imposed on this structure by the support of the sturdy inner sole 17 which assists the upper 19 at the point where weight is applied by a naturally curved section at that point.

Now referring to Fig. 9 it will be observed that the inner sole 17 is again carried on its inner side by supporting structure and the weight is again shifted to the outside of the foot by the natural curve formed thereby. As a detail, it will be observed that there is a slight arch at the center line 12, which conforms to the shape of the normal foot structure.

Now referring to Fig. 10 it will be observed that at this section, the formed inner sole 17 is slightly concave to provide a relatively flat concaved section for the toe section of the shoe.

I again repeat and emphasize that my formed inner sole 17 is made of strong stiff leather of substantial thickness formed under heat and pressure to provide a strong rounded side wall support for the bottom of the foot and that it is mounted firmly and securely on the sole of the shoe to provide an effective coacting member which protects the counter and upper from excessive stresses imposed by carrying the weight of the wearer on the outside of the foot. Although I have described a preferred form of inner sole made of leather, it will be understood that any other material such as phenolic condensation

products or plastics of other kinds may be substituted.

Now having described my improved cradle support sole structure, I desire to point out and teach that such structure requires the upper of the shoe to be proportioned and formed in a particular manner in order to be completely coercive and effective. Having arranged to carry the weight on the outside of the foot, it is necessary to form the upper in proper coacting relationship.

Shoe manufacturers have gradually developed a shoe last in a wide variety of sizes and shapes which experience has taught will fit a high percentage of all human feet. The large, reputable manufacturers of lasts regularly list twenty-six sizes of men's shoes in eleven widths, or a total of two hundred eighty-six sizes. The circumferential measurements of these lasts are given for the ball, waist and instep and they are given in inches and eighth inches. For instance, size 7, width A—ball 8, waist 7 $\frac{1}{2}$, instep 8 $\frac{1}{2}$; size 8A—ball 8 $\frac{1}{2}$, waist 8 $\frac{1}{2}$, instep 8 $\frac{1}{2}$; size 7D—ball 8 $\frac{1}{2}$, waist 8 $\frac{1}{2}$, instep 9 $\frac{1}{2}$; size 8D—ball 9, waist 8 $\frac{1}{2}$, instep 9 $\frac{1}{2}$.

I have found that in order to properly fit shoes having my improved outwardly inclined inner sole, which carries the weight of the wearer on the outside of the foot, I must maintain the cross sectional sizes for proper fit by compensating for the rounded bottom inner sole and sidewise positioning of the foot. I therefore must add to the upper last such areas as are removed from standard lasts by my concaved formed inner sole. I do this in exact proportion to the displacement of the last material by adding such displacement to the upper side of the last in smoothly flowing contours. I have found that this provides the necessary space for the normal foot tissues when carrying weight on its outside and further that this provision induces the foot into proper shape for functioning in the desired natural manner.

As an example, if one would take a standard flat bottom last and remove the bottom material to provide the rounded cradle heel and high rounded shank, in accordance with my teaching, substantially all the material removed should be added to the opposite upper section of the last in smooth proportioned contours.

I have found that lasts so produced correspond

almost exactly to the shape produced by a normal human foot imbedded in sand and molded to the shape of the foot when carrying its normal weight on the outside of the foot in accordance with my theory.

It has been my observation and experience that shoes constructed in accordance with my theory and teaching, do function in the manner described, and wearers are greatly benefited by my improved shoe design and structure.

Having thus described my invention, I now claim as new:

1. A shoe comprising a heel and sole structure, an insole, a counter, and an upper, said heel and sole structure and said insole providing a foot supporting surface comprising a raised untilted cupped heel portion shaped to conform to the contour of the heel of a normal foot and having substantially uniformly curved side and rear portions with the curvature at the outside of the shoe from a point within and near the front end of said heel portion gradually lowering toward, in and through the shank portion at a greater slope than the curvature at the inside of the shoe to provide an outwardly tilting surface with curved sides at the front of said heel portion and in said shank portion, said curved sides then gradually diminishing in curvature and gradually leveling to provide a substantially flat untilted surface at the ball portion of the shoe.

2. A shoe last having a raised untilted convex heel surface with the side and rear portions thereof substantially uniformly curved, the curvature at the sides continuing forwardly and gradually lowering from a point within and near the front end of the heel surface toward, in and through the shank portion with the curvature at the outside of the last lowering at a greater slope than at the inside to provide an outwardly tilting surface with curved sides in the front part of said heel surface and in said shank portion, said curved sides then gradually diminishing in curvature and gradually leveling relative to each other to provide a substantially flat untilted surface at the ball portion of the last, said last with its curved sides being shaped to conform to and having sufficient cross-sectional area throughout its length to fit the contour of a normal foot.

RICHARD E. FREEMAN.
